Specification for Design.

Patented Aug. 29, 1916.

Application filed May 18, 1916. Serial No. 98,459. Term of patent 7 years.

To all whom it may concern:

Be it known that I, GEORGE E. CURTISS, a citizen of the United States, residing in the city of New Britain, county of Hartford, and State of Connecticut, have invented a certain new, original, and ornamental Design for Handles for Forks and Similar Articles, of which the following is a full, clear, and exact description, reference being had to the accompanying drawings, forming a part thereof.

Figure 1 is a back view of a handle attached to a fork and embodying my invention; Fig. 2 is a front view of the same, and Fig. 3 is a cross section of the handle at its largest part.

I claim—

The ornamental design for a handle for forks and similar articles, as shown.

GEORGE E. CURTISS.
